(57) CLAIM

The ornamental design for a handbag, as shown and described.

DESCRIPTION

FIG. 1 is a front perspective view of a handbag showing my new design;

FIG. 2 is a front view of the handbag shown in FIG. 1;

FIG. 3 is a rear view of the handbag shown in FIG. 1;

FIG. 4 is a side view of the handbag shown in FIG. 1;

FIG. 5 is the other side view of the handbag shown in FIG. 1;

FIG. 6 is a top view of the handbag shown in FIG. 1;

FIG. 7 is a bottom view of the handbag shown in FIG. 1;

FIG. 8 is a front perspective view of the handbag shown in FIG. 1, with handles and flaps shown in a raised position;

FIG. 9 is a front view thereof;

FIG. 10 is a rear view thereof;

FIG. 11 is a side view thereof;

FIG. 12 is the other side view thereof;

FIG. 13 is a top view thereof; and,

FIG. 14 is a bottom view thereof.

The broken lines depict portions of the handbag in which the design is embodied in environmental matter and is not considered part of the claimed design in those figures.
